UNITED STATES PATENT OFFICE.

WILLIAM S. BULLEN, OF INDIANAPOLIS, INDIANA, ASSIGNOR TO HIMSELF AND STEPHEN A. CLARK, OF SAME PLACE.

MACHINE FOR CREEASING LEATHER.

Specification of Letters Patent No. 30,785, dated November 27, 1860.

To all whom it may concern:

Be it known that I, WILLIAM S. BULLEN, of Indianapolis, in the county of Marion and State of Indiana, have invented a new and useful Improvement in Creasing-Machines for the Use of Carriage-Trimmers, Harness-Makers, and other Workers in Leather; and I do hereby declare that the following is a full and exact description thereof, reference being had to the accompanying drawings, and to the letters of reference marked thereon.

The nature of my invention consists in substituting chased rotary disks of metal for the old and time-honored "creasing tool", and so operating said "disks" as to make the whole design at one passage over the leather, all of which I do by the simple process of turning a crank.

To enable others skilled in the art, to make and use my invention, I will proceed to describe its construction and mode of operation; and, in this description, I desire that the accompanying drawings shall constitute a part and parcel of said specification, and in every instance where reference is made to a part of my machine by letter, I wish it understood that each like letter refers to a like part.

Figure 1, is an elevated perspective view of my entire machine (with a small portion of the table cut away so as to show the large propelling roller beneath said table). Fig. 2, is a combination of circular disks which are used for creasing as they appear on the edge. Fig. 3, is the diameter view of the creasing disks, as seen in Fig. 2. Fig. 4, is an edge view of a single disk. Fig. 5, is the thimble, or spool upon which the creasing disks revolve; and Fig. 6, is the shaft which passes through the thimble or spool, Fig. 5.

A, is the table, upon which my creasing wheels, and all their appurtenances are arranged. This table is supported by four legs of any desired length. These legs must be long enough to give a clear and free sweep to the crank (H).

B, is a crane neck bracket one end of which is firmly fastened by screws to the table (A)—and the other end carries the

graduated slide which adjusts the creasing disks (E). It must be made of iron.

(C,) is the graduated slide which is moved up and down by the screw (D) and carries 55 the creasing disks (E) by means of which they are adjusted to suit the thickness of the leather, which passes between them and the roller (F), as seen in Fig. 1. The roller (F,) is revolved by turning crank (H) 60 which is fastened on the right-hand end of the shaft (G.) The pin, or shaft (J,) passes through the thimble, or spool (I) and upon it the said spool fits loosely.

It will be seen that the creasing disks may 65 be made of any desirable pattern, so far as the chasing on their periphery is concerned; and since each one is independent of all the others, and all of the same diameter, they may be changed to suit the taste of the 70 operator, and so compounded as to vary the designs to almost any extent.

The mode of operation is simple, viz: Having placed the leather (to be creased) between the creasing disks (E,) and the 75 roller (F,) in (Fig. 1,) turn down the screw (D) until the leather is tightly compressed, then by turning the crank (H) the leather is forced through between the roller and creasing disks in such manner as to make a 80 firm and lasting impression.

The advantage of this expeditious mode of doing this kind of work, is self-evident. By this means, the work of a whole day (with the old fashioned "ticler,") can be 85 done in ten or fifteen minutes; and, when done, is far more systematic and uniform.

This machine is designed for carriage trimmers, and other workers in leather, and, having thus fully described the nature of 90 my invention and the mode of its operation

What I claim as new, and desire to secure by Letters Patent, is—

The combination and arrangement of a series of creasing disks, (E) upon, and with 95 spool or thimble (I,) when these are made to revolve upon axle (J,) substantially as shown, and for the purposes designated.

W. S. BULLEN.
